UNITED STATES PATENT OFFICE.

WILLIAM J. BURT, OF HOLLAND, MICHIGAN.

SIGNALING DEVICE FOR AUTOMOBILES.

Application filed March 3, 1928. Serial No. 258,980.

This invention relates to signaling devices for automobiles and more particularly to a mechanically operated signal embodying a plurality of arms which may be selectively extended predetermined distances to give different signals.

An important object of the invention is to produce a device of this character in which the operating parts may be compactly arranged and may be simply and cheaply manufactured, while, at the same time, producing a durable and efficient signal.

A further object of the invention is to provide a device of this character which is readily adjustable to enable variations of the positions of the arms when in signaling position, due to wear upon the connections, to be compensated for.

A further object of the invention is to produce a device of this character which, when applied to the automobile, will be neat in appearance.

These and other objects I attain by the construction shown in the accompanying drawings, wherein for the purpose of illustration is shown a preferred embodiment of my invention and wherein:—

Figure 1 is a fragmentary front elevation showing a signal, one of the signaling elements being in signaling position;

Figure 2 is a horizontal sectional view through the operating mechanism;

Figure 3 is a vertical sectional view on the line 3—3 of Figure 2;

Figure 4 is a section on the line 4—4 of Figure 2;

Figure 5 is a diagrammatic view showing the connections to the signal illuminating elements.

Referring now more particularly to the drawings, the numeral 10 generally designates the cowl of an automobile, 11 the instrument board thereof and 12 the windshield. In accordance with my invention, I arrange beneath the cowl immediately in advance of the instrument board a casing 13 having rotatably mounted in the side walls thereof a plurality of parallel transversely extending shafts 14. The casing has a partition wall 15 extending thereacross and slidably mounted in the slots 16 formed in this partition are bars 17, each having a portion thereof formed as a rack 18. The forward ends of the bars are cir-

cular in cross section, as indicated at 19, and are directed through openings formed in the front wall 20 of the casing and through aligned openings formed in the instrument board 11. At their forward ends, they are provided with eyes 21 or other suitable heads for engagement by the hand of the operator. Each shaft 14 has secured thereto a gear 22 aligning and coaxing with one of the racks 18. The racks 18 are of different lengths, so that the shafts 14 are rotated through different distances upon an actuation of the associated bar 17.

One side wall 23 of the casing is provided with a vertical guide slot 24 adjacent each shaft 14 and in these guide slots are disposed vertical racks 25, which engage with gears 26 carried by the associated shaft. Each rack has at its upper end an extension 27 which is circular in cross section and has its upper end threaded for engagement with a head 28. These circular extensions project through an opening formed in the cowl 10 and into the lower end of a casing 29 carried by the cowl. This casing has front and rear walls connected by a horizontal pivot 30 extending longitudinally of the vehicle and upon which are mounted signal arms 31 corresponding in number and arrangement to the shaft. Each signal arm has an angular extension 32 which is connected intermediate its ends to the upper end of a link 33, the lower end of which is connected to the head of the associated rack. The casing embodies a horizontal bracket paralleling the pivot 30, as indicated at 34, against which the free ends of the angular extensions engage when the signals are vertically disposed and concealed between the casing walls.

The signal arms 31 are preferably tubular, providing conduits for electric wires 35 leading to the illuminating elements of signaling heads 36 carried by the outer ends of these arms. These signaling heads may be provided in one or both faces with indicia bearing lenses 37.

The casing 13 is provided on the inner face of its front wall with contacts 38 adapted for connection with one terminal of a source of current, the opposite terminal of which is electrically connected with the illuminating elements of the signals. Each bar 17 carries a contact 39 for engagement with a con-

tact 38 of the casing when the signal is in its operative position, so that as the signal comes to its operative position, the circuit of the illuminating element is completed.

- 5 It will be obvious that in some instances, instruments carried by the instrument board 11 will prevent placement of the casing 13 at a point where the bars 25 may conveniently project directly upwardly from the 10 normal position of the side wall 23. To this end, this side wall is preferably detachably connected with the remainder of the casing having an angular extension 40 underlying the casing and adjustably secured thereto. 15 The shafts 14 are made of sufficient length to permit adjustment of the wall 23 and the gears 22 are each provided with a hub 41 for the passage of a securing element by means of which they may be secured in 20 adjusted positions upon these shafts. By employing this structure, the casing may be conveniently disposed as regards the position of the vertically movable bars 27.

It will, of course, be understood that the 25 lenses of the signaling elements will be provided with suitable indicia, such as S, indicating "Stop" and R and L indicating "Right" and "Left" respectively.

It will be obvious that a construction of 30 this character may be readily adapted to any signaling code and may be readily applied to the vehicle. Since adjustments may be very readily made to compensate for wear, an accurate signaling device is provided. 35 Since the construction hereinbefore set forth is capable of a certain range of change and modification without materially departing from the spirit of the invention, I do not limit myself to such specific structure except as hereinafter claimed.

I claim:

1. In combination with a vehicle including a cowl, a casing arranged beneath the cowl, a shaft rotatable in the casing, a bar 45 reciprocatable in the casing and having connection with the shaft whereby the shaft is rotated as the bar is reciprocated, a vertically extending bar guided by the casing and at its upper end projecting through an opening in the cowl, a connection between said last named bar and the shaft whereby the bar is vertically 50

shifted when the shaft is rotated, and a signal operated by the upper end of the bar.

2. In combination with a vehicle including 55 a cowl, a casing arranged beneath the cowl, a shaft rotatable in the casing, a bar reciprocatable in the casing and having connection with the shaft whereby the shaft is rotated as the bar is reciprocated, a vertically 60 extending bar guided by the casing and at its upper end projecting through an opening in the cowl, a connection between said last named bar and the shaft whereby the bar is vertically 65 shifted when the shaft is rotated, a housing including spaced walls supported by the cowl, a pivot connecting said walls, a signal mounted upon the pivot having an angular portion connected with the upper end of the last named bar. 70

3. In a signal element, a casing, a plurality of bars reciprocatable in the casing, a shaft associated with each bar to be rotated by the reciprocation thereof, a second bar associated with each shaft and vertically 75 shifted by rotation thereof, and a pivoted signal element associated with each of the last named bars and shifted about the pivot thereof by reciprocation of said bars, said shafts having bearing in the side walls of 80 the casing, one of said side walls providing guides for the second bar associated with each shaft.

4. In a signal element, a casing, a plurality of bars reciprocatable in the casing, a shaft 85 associated with each bar to be rotated by the reciprocation thereof, a second bar associated with each shaft and vertically shifted by rotation thereof, a pivoted signal element associated with each of the last named 90 bars and shifted about the pivot thereof by reciprocation of said bars, said shafts having bearing in the side walls of the casing, one of said side walls providing guides for 95 the second bar associated with each shaft, said side walls being detachably connected with the casing, and means supporting the side wall from the casing permitting adjustment of said side wall toward and away from the other of the side walls. 100

In testimony whereof I hereunto affix my signature.

WILLIAM J. BURT.
